BACK AND HEAD SUPPORT ASSEMBLY FOR DENTAL CHAIR

David R. Gillham, 2872 Plass, Topeka, Kans. 66611

Filed July 13, 1972, Ser. No. 271,391

Term of patent 14 years

Int. Cl. D6—06

U.S. Cl. D6—200

Fig.2.

Fig.1.

Fig.4.

Fig.3.

FIG. 1 is a front elevational view of a back and head support assembly for dental chair, showing the head support extended;

FIG. 2 is a side elevational view thereof;

FIG. 3 is a top plan view; and

FIG. 4 is a front elevational view of the back and head support assembly for dental chair showing the head support retracted.

I claim:

The ornamental design for a back and head support assembly for dental chair, as shown.
